SAFETY CLOSURE DEVICE FOR CONTAINERS OF VOLATILE LIQUIDS

John Essendon Simmonds, Toorak, Victoria, and
Charles Peterson, Elsternwick, Victoria, AustraliaApplication April 12, 1932, Serial No. 604,824, and
in Australia April 13, 1931

6 Claims. (Cl. 220—88)

This invention relates to an improved closure device or fitting for containers or tanks to prevent the ignition of contained volatile liquids or of their vapours.

3 Fittings have been used previously which are inserted in the opening of these containers and provided with wire gauze or perforated metal with round holes, the diameters of these round holes being equal to the thickness of the material and consequently being quite large if the material is relatively thick. In some cases these devices have minimized considerably the danger of explosion due to a flame flashing back into the container, but they have not been entirely efficient where the conditions of storage are such that the liquids or their vapours are in an especially dangerous state, for instance if the volatility of the liquid be increased by an excessive rise of temperature or again if the air and vapour 15 are present in proportions most likely to explode. For these reasons it has been found that these prior safety devices are unreliable and, by producing unwarranted confidence may even constitute a source of danger.

25 The object of the present invention is to prevent the possibility of a flame striking back into the container.

The fitting is constructed in the form of a conical or like shaped perforated metal screen 30 which is inserted through the filling aperture of the vessel so that it projects into the vessel, the perforations being conical so that the openings at that side or surface of the fitting which faces the atmosphere are smaller than the openings at 35 that side or surface of the fitting which faces the liquid in the vessel. This results in the flame being brought into very close contact with the material in the event of the vapour issuing from the container and catching a light and striking 40 back into the fitting. This conical shape of the perforations is of great importance in preventing the flame from passing through them into the main portion of the container. It is believed that the conical shape of the perforations causes 45 the flame to spread in the same way that a similarly shaped nozzle on a garden hose tends to spread a water spray. It would appear that this brings the flame into close contact with the metal and thereby not only tends to cool the flame but 50 also tends to smother the flame to some extent by preventing air passing down behind the flame and consequently the flame is supplied with air from one side only. In any case, whether this is the correct theory or not, the shape of these holes 55 undoubtedly has a marked effect in reducing the

possibility of a flame passing through them into the container.

The invention will be described in relation to the accompanying drawing which illustrates the preferred construction of this invention. In the 60 drawing:

Figure 1 is a vertical central section through the device, the neck of the filler port of the container being shown in chain dotted lines.

Figure 2 is a perspective view of the device 65 removed from the container, and

Figure 3 is an enlarged sectional view of a portion of the perforated metal.

According to this preferred construction the device or fitting has a body 1 formed of sheet 70 copper comprising a conical portion 2 and a neck 3 which are both provided over their whole surfaces with conical perforations 4. The exact size and number of these perforations are of importance. After very extensive experiments it has 75 been found that the greatest efficiency by far was obtained if the holes were $\frac{1}{2}$ of an inch in diameter on the inside surface of the fitting, or in other words if the smallest diameter of each hole was of that size, and if 250 of these perforations 80 were provided to the square inch. When this number of perforations is provided the centers of adjacent perforations will be .068 of an inch apart.

A further important constructional feature is 85 that the device is cone-shaped and has a neck 3 which is angular in cross-section, being polygonal or even square or triangular but preferably being octagonal or hexagonal. This enables petrol (gasoline) or other volatile liquid to be poured 90 through the device into the container without any of the liquid being blown out through the neck and port owing to the upward surging of escaping air or vapour. The corners 5 of the 95 octagon or other polygon enable the air and vapour to escape because the liquid tends to keep to the more central portion of the passageway through the neck. A top portion of the neck may be turned outwardly to form a flange 6 which is brazed or otherwise suitably attached to a collar 7 or other suitable member by which it is secured by rivets 8 or other known means to the neck 9 of the filler port. The collar 7 and neck 9 may be of any suitable known type of construction and are indicated on the drawing somewhat diagrammatically for that reason. The conical shape of the body of the fitting is of special value when the fitting is included in pipe lines or leads or other passageways where it is important that the effective area of the passageway shall not be 100 105 110

unduly restricted. The conical shape enables a great number of the small perforations to be provided so that the total area of the perforations may be even greater than the cross sectional area of the passageway.

The device may also be employed for preventing the passage of a flame along pipes or like leads where the combustible vapour of volatile liquids is present.

10 What we do claim as our invention and desire to obtain by Letters Patent is—

15 1. A safety device for an opening of containers for volatile liquids to prevent the ignition of the volatile liquids or their vapours and passage of flame, comprising a conical or like shaped metal screen provided with a large number of perforations which are smaller at their ends on the atmospheric side of the screen than they are at the vapor contacting side.

20 2. A safety closure device for preventing the ignition of volatile liquids as claimed in claim 4 and in which the perforations are substantially $\frac{1}{2}$ of an inch in diameter and with the centers of adjacent perforations substantially .068 of an inch apart.

25 3. A safety closure device for preventing the ignition of volatile liquids as claimed in claim 1 having a neck polygonal in cross-section to facilitate the escape of air when the volatile liquid is poured through the device into the container.

4. An ignition-preventing screen for disposition between a volatile liquid and the atmosphere, the screen having a multiplicity of perforations therethrough, said perforations being substantially frusto-conical with their larger ends at the liquid-facing surface of the screen.

5. An ignition-preventing screen for disposition between a volatile liquid and the atmosphere, the screen having a multiplicity of perforations therethrough, the defining walls of said perforations being disposed out of parallelism to lines right-angularly intersecting the screen, said perforations being larger at the side of the screen which faces the liquid than at the other side thereof.

6. An ignition-preventing screen according to claim 4 wherein the screen is obliquely disposed.
